UNITED STATES PATENT OFFICE

NORMA McDONALD BURMEISTER, OF CHICAGO, ILLINOIS

POWDER PUFF

Application filed November 28, 1928. Serial No. 322,316.

My invention relates to powder puffs. It relates more particularly to an improved magazine type of powder puff adapted to be carried in a lady's purse.

5 I am aware that suggestions have been made with the idea of carrying face powder on the interior of a receptacle which is at the same time adapted for use in the spreading of the powder on the face. These prior 10 devices have not met with satisfaction for reasons which will appear obvious in connection with the description of my improved device.

The principal object of the present invention is the provision of an improved powder puff.

Another object is the provision of a powder puff of improved design adapted for carrying a supply of powder within the puff.

29 Another object is to modify the present standard type of powder puff to permit the carrying of a supply of powder within the puff itself.

Another object is the provision of a powder puff adapted for carrying a supply of powder, and at the same time possessing all of the advantages of compactness, texture and convenience which the present day standard powder puffs have.

30 Other objects and features of the invention will be apparent from a consideration of the detailed description taken with the accompanying drawings wherein

Fig. 1 is a plan view showing my improved powder puff with the outside cover partially broken away to show the construction thereof;

Fig. 2 is a sectional view thereof taken along the line 2-2 of Fig. 1 and

40 Fig. 3 is an end view of the powder puff showing the manner in which it may be retained in a folding position when not in use.

Referring now to the drawings the body 45 of the puff comprises the usual outside circular members 10 and 11 and an inside padding 12 of proper substance to furnish the necessary body and stability. Within the puff a pocket 13 is provided, the padding 50 being entirely removed or its thickness de-

creased to provide this pocket. It is within a magazine carried by this pocket that I carry the powder 14.

The pocket is provided with a small sack for containing the powder comprising a 55 layer of closely woven silk 16 or similar material but with a screen material 17 at the top thereof and immediately in communication with the apertures 18 provided in the outside cover 10. These apertures are 60 maintained at open position in any suitable way but I prefer the employment of eyelets 19 preferably made of celluloid or similar material, or with thin metal covered with a 65 white lacquer. In either case the eyelets 70 should not be too conspicuous on the face of the puff.

For securing the puff together the usual stitching 21 is provided throughout the main portion of the puff to hold the members 10 75 and 11 together. At the pocket 13 I have the material 16 and 17 comprising the section in which the powder is held or sewed to the inturned edges 10a and 11a of the cover members. Complementary fastening members 22 are provided in sufficient number to hold the opening to the pocket in closed 80 position when the puff is in use. The fastening members, preferably snap fasteners, are arranged, however, so that the opening to the puff can be quickly opened for the purpose of replenishing the supply of powder.

I employ a screen material 17 of such a density that in ordinary use of the powder puff the powder will not be spilled through the holes in the cover. When the pocket portion of the puff, however, is tapped gently against the face small beads of powder will be deposited on the skin, and the screen is designed to admit just enough powder for this operation but not too much.

Although with ordinary handling powder will not be spilled from the puff it may be desired to protect the top face of the puff 95 when it is carried in a hand bag or about the person. To arrange for this I sew a short strip of ribbon 23 to the edge of the puff opposite the pocket 13 and secure to the outer edge of the ribbon a snap fastener 100

24. A complementary fastener 26 is secured to the puff immediately below the pocket so that the puff can be bent in two as shown in Fig. 3 and secured in this position by extending the ribbon 23 around and fastening the fasteners 24 and 26.

What I claim as new and desire to protect by Letters Patent of the United States is:

10 1. The combination with a standard powder puff having an outside cover and inside packing material to impart body to the cover, of a powder receiving pocket formed in the packing material, said pocket 15 comprising a sack having a portion thereof formed of screen material, and holes being provided in the outside cover communicating with the screen adapted for the discharge of powder by dusting the thickness of a small area of the packing material being decreased to provide space for the pocket.

2. In a powder puff, an outside cover, an inner body forming material having a small 25 area of less thickness than the major portion thereof, a powder magazine in the form of a pocket comprising an imperforate cloth on one side and screen material on the other side disposed inside the cover in said small 30 area, and means for discharging a small supply of powder from the pocket onto the skin when the puff is patted thereon.

3. In a powder puff, an outside cover, an inner body forming material having a small 25 area near the edge of the puff of less thickness than the major portion thereof, a powder magazine in the form of a pocket comprising an imperforate cloth on one side and screen material on the other disposed inside the cover in said small area, 40 said magazine having an edge opening for inserting powder, and means for retaining the edge opening in closed position, openings from the magazine through the outer 45 cover being provided.

4. In a powder puff, an outside cover, an inner body forming material having a small area of less thickness than the major portion thereof, a powder magazine in the form 50 of a pocket comprising an imperforate cloth on one side and screen material on the other and disposed inside the cover in said small area, said magazine having an opening for inserting powder, means for normally retaining said opening closed, having openings through the outer cover, and means for keeping said puff in a folded position to cover the openings in said outside cover when the puff is not in use.

55 60 In witness whereof, I hereunto subscribe my name this 17th day of November, 1928.

NORMA McDONALD BURMEISTER.
